CLAIM

The ornamental design for a medical injector, as shown and described.

DESCRIPTION

The file of this patent contains at least one photograph executed in color. Copies of this patent with color photographs will be provided by the Office upon request and payment of the necessary fee.

FIG. 1 is a front elevation view of a first embodiment of a medical injector showing my new design;
FIG. 2 is a right side view thereof;

FIG. 3 is a rear view thereof;

FIG. 4 is a left side view thereof;

FIG. 5 is a perspective view thereof;

FIG. 6 is a top plan view thereof;

FIG. 7 is a bottom view thereof;

FIG. 8 is a front elevation view of the second embodiment of a medical injector showing my new design;

FIG. 9 is a right side view thereof;

FIG. 10 is a rear view thereof;

FIG. 11 is a left side view thereof;

FIG. 12 is a perspective view thereof;

FIG. 13 is a top plan view thereof;

FIG. 14 is a bottom view thereof;

FIG. 15 is a front elevation view of the third embodiment of a medical injector showing my new design;

FIG. 16 is a right side view thereof;

FIG. 17 is a rear view thereof;

FIG. 18 is a left side view thereof;

FIG. 19 is a perspective view thereof;

FIG. 20 is a top plan view thereof; and,

FIG. 21 is a bottom view thereof.
